RAILWAY HOPPER CAR OUTLET

John J. McBride, Bayonne, and Victor Willoughby, Ridgewood, N. J., assignors to American Car and Foundry Company, New York, N. Y., a corporation of New Jersey

Application April 18, 1939, Serial No. 268,560

10 Claims. (Cl. 105—247)

This invention relates to hopper outlets in general and in particular to such outlets for use on railway hopper cars for the transportation of fine ladings which must be kept dry.

In the past, hopper outlets for cars intended to carry fine ladings that must be kept dry have been of the sliding type operating in sealing grooves but with outlets of this type considerable trouble has been experienced due to the fact that the sliding gates are hard to operate and extremely hard to close due to the lodgment of lading in the slides or grooves. It has also been almost impossible to prevent the entrance of moisture since the extended portions of the slides form a ledge upon which snow and ice may collect gradually seeping into the lading during meltage. It is an object, therefore, of the present invention to provide a railway hopper car with a new and improved outlet casting which is absolutely waterproof.

A further object of the invention is the provision of a new and improved outlet casting for railway hopper cars having swinging doors substantially encased at all times in the outlet casting.

A still further object of the invention is the provision of a new and improved outlet casting for railway hopper cars equipped for the attachment of a discharge chute and with swinging doors operable after the attachment of the chute.

Yet another object of the invention is the provision of a new and improved outlet casting for railway hopper cars together with a new and improved door operating and locking arrangement carried within the casting.

These and other objects of the invention will be apparent to persons skilled in the art from a study of the following description and accompanying drawings, in which

Figure 1 is an end elevational view of one of the improved hoppers with parts broken away and in section to more clearly disclose the construction;

Fig. 2 is an outside elevational view of the hopper shown in Fig. 1;

Fig. 3 is a sectional view taken substantially on line 3—3 of Fig. 1;

Fig. 4 is an inverted plan view of the hopper with a portion thereof broken away to better disclose the construction;

Fig. 5 is a sectional view taken substantially on line 5—5 of Fig. 2, and

Fig. 6 is a sectional view taken substantially on line 6—6 of Fig. 2.

Referring now to the drawings in detail, it will

be seen that the improved door arrangement and outlet casting has been applied to a hopper outlet forming part of a car such as shown in Patent 2,024,342. The hopper is formed by an inner sheet 2, side slope sheets 4 and an outer slope sheet 6, the latter reinforced by an angle 8. Such hopper construction is merely representative for it is obvious that other types of hoppers and hopper sheet arrangements may be used without departing from the spirit of the present invention.

The hopper outlet casting in the present instance is generally box shaped and consists of an inner end 10, outer end 12 and side walls 14, all of which merge into an upper top wall 16. This upper or top wall is formed with an opening 18 substantially of the same size as the hopper discharge outlet and the edges of this opening are reinforced by upstanding flanges 20 formed to conform to the hopper sheets to which they are attached. The lower edges of the end and side walls of the casting merge into outwardly directed flanges 22 pierced as at 24 for reception of bolts or other securing means 26. The bolts or securing means as clearly shown in Figs. 1, 2 and 6 are adapted to retain an angular form frame 28 by means of which a safety plate 30 may be clamped against a sealing gasket 32, thus effectively sealing the box-like casting and forming in effect a removable bottom. The sides of the angle frame 28 preferably have secured thereto clips 34 adapted to slide along the side flanges 22 in order to retain the safety plate or removable bottom in position while the bolts 26 are being placed or removed. The box-like outlet casting is also formed with roughly triangularly shaped flanges 36 projecting into the box and located substantially in alignment with the inner and outer edges of the hopper outlet and in spaced relation to the inner and outer end walls of the casting. The lower edges of these triangularly shaped flanges are adapted to receive rubber gaskets 38 projecting below the edges of the flanges and held in place by metal strips 40. These strips and gaskets also extend along the sides of the opening adjacent the lower edges of the side attaching flanges 20, thus in effect a resilient rubber gasket is provided entirely around the discharge outlet.

The inner and outer end walls 10 and 12 of the casting are formed with bosses 42 located beneath the upper wall of the casting and to one side of the outlet opening. These bosses are drilled or cored to receive hinge rods 44 adapted to extend through the eyes 46 formed on the

edges of the swinging doors 48. As shown, the hinge rods 44 are held in position and sealed against the entrance of water by being welded in place as at W. Attention is directed to the fact that the hinge rods are so positioned and the doors so designed as to permit the doors to hang substantially vertically when in the open position (see Fig. 3). The lower outer corners of the end wall 10 are formed with bosses 50 providing pockets opening into the box-like casting and adapted to receive inner end 52 of door operating and locking rod. Each door operating and locking rod is formed with an offset door engaging portion 54 joined to the inner end 52 and to the outer end 56 by angular portions 58. The inner end of each door operating and locking rod has a collar 59 shrunk thereon and adapted to be overlapped by a bracket 60 riveted to the inner end wall of the casting, thus securely holding the door locking and operating rod in position without any possibility of entrance of moisture. The outer end 56 of each door operating and locking rod extends through a boss 61 formed on the outer end wall and this boss is threaded as at 62 (Fig. 6) to receive a packing nut 63 by means of which packing 64 may be compressed to seal the outer wall against entrance of any moisture to the interior of the casting. The packing engages against the casting and against a shoulder 65 formed on an operating arm 66 keyed or otherwise secured to the shaft end 56. The offset portion of each door operating and locking rod is adapted to contact and ride along cams 68 preferably cast as reinforcing ridges on the lower surface of each door 48. As clearly shown in Figs. 2 and 3, each of these cams has the portion nearest the door hinge formed relatively flat, while the portion remote from the door hinge or adjacent the free edge of the door is formed at a relatively sharp curvature in order that the doors may be more positively lifted to their final position and in order that the locking rod can not be moved out of engagement with the door as it moves toward locking position.

The outer end wall is formed intermediate its substantially adjacent center line with a boss 70 adapted to receive a bolt or other means 72 upon which the lower portion of an operating lever 74 may be pivoted. This lever carries spaced pins 76 located an equal distance on either side of the pivot bolt 72 and these pins are connected by means of straps or other connecting links 78 to pins 80 carried by the operating arms 66 previously referred to. The upper or free end of the operating lever is formed with a handle portion 82 by means of which the lever may be swung to either open or close and lock the doors. Final locking and sealing of the doors is accomplished by engaging the operating lever between spaced plates 84 carried on the reinforcing angle 8 and these plates are provided with a plurality of holes 85 adapted to receive sealing pin 86. It should be noted that the openings 85 are staggered and so positioned as to give an extremely fine adjustment as to the positioning of the operating lever. In this way the lever may be used to compensate for wear on the door parts and always lock the doors in fully closed position.

Assuming the doors to be in the locked position shown in Figs. 1 and 2, the operation of the device is as follows: Removal of the sealing pin will permit the operating handle to be moved in a counter-clockwise direction causing the connecting links 78 to impart a thrust to the arms 66. The thrust imparted to these arms will cause

the door operating and locking rods to rotate in opposite directions, that is, one will rotate clockwise, while the other rotates counter-clockwise but their rotation is simultaneous and as they 5 rotate the offsets 54 will ride along the cams 68 permitting the doors to open under the weight of the lading. In fact, once the opening movement of the doors has been instituted the weight of the lading will force the doors to the fully open 10 position as shown in Fig. 3 in which they line up substantially with the openings in the upper wall of the casting. If the material carried by the hopper is of an extremely powdery nature or must be kept absolutely dry, a boot or discharge chute is attached to the flanges 22 after the safety sealing plate 30 has been removed. After attachment of the boot the doors may be 15 operated as previously discharging the material from the car without any possibility of the lading becoming wet or being wasted by blowing away.

It should be noted that the hinge rod and door operating rods are effectively sealed against entrance of moisture or exit of lading and that 20 leakage of lading from the hopper past the doors is effectively prevented by the gaskets which may be heavily compressed by the operating lever since a very powerful leverage exists between the operating handle and the cams 68 to force the doors into closed position. The use of the safety plate 30 prevents any moisture or dirt from 25 entering into the box-like casting, thus insuring not only dry lading but that the lading may be discharged in a pure condition which is absolutely necessary in case sugar or certain chemicals are 30 being transported.

While the invention has been described more or less in detail, it is obvious that various modifications and rearrangements of parts may be 35 made by persons skilled in the art and all such modifications and rearrangements of parts are contemplated as will fall within the scope of the following claims:

What is claimed is:

1. In a railway hopper car the combination of a hopper formed in part by metallic sheets converging to provide a hopper discharge opening, a frame secured to the sheets adjacent the said opening, said frame being formed with a top portion having an opening therein registering with said hopper discharge opening and also formed with relatively deep downwardly directed side and end walls spaced laterally outward from the edges of said opening, and doors for closing said opening, said doors being hinged to certain of said walls adjacent the top portion of the frame, said hinges being spaced laterally outward from the edges of the opening whereby the doors will be substantially inclosed at all times by said walls and will not restrict flow of lading through the hopper discharge opening.

2. In a railway hopper car the combination of a hopper formed in part by metallic sheets converging to provide a hopper discharge opening, a frame secured to the sheets adjacent the said opening, said frame being formed with a top portion having an opening therein registering with said hopper discharge opening and also formed with relatively deep downwardly directed side and end walls terminating in outwardly directed flanges, said side and end walls being spaced laterally outward from the edges of said hopper discharge opening, doors hinged to certain of said walls adjacent said top portion whereby the doors will be substantially inclosed at all times by said

walls, said hinges being spaced laterally outward from the edges of the opening whereby said doors when open will occupy the space between the side walls and adjacent edges of the hopper discharge opening thereby giving an unrestricted flow of lading through the hopper discharge opening, safety cover secured to said flanges and preventing entrance of foreign matter into said frame.

3. In a railway hopper car having a hopper discharge opening formed in part by converging metallic hopper sheets, the combination of an outlet frame formed with a top portion having an opening therein registering with said hopper discharge opening, means securing said top portion to the metallic hopper sheets, frame side and end walls depending from said top portion in laterally outwardly spaced relationship to the edges of said hopper discharge opening, doors hinged on certain of said walls by hinge rods located adjacent said top portion, said doors having their free edges meeting adjacent the center of the frame, door operating rods pivotally carried by certain of said walls adjacent the lower edges thereof and laterally outward of the edges of the hopper discharge opening, said operating rods having a portion thereof extending through the frame, and operating means secured to said rod extensions exterior of the frame, said hinge rods and operating rods being sealed with respect to the frame thereby preventing entrance of foreign matter into the frame through the side walls thereof.

4. In a railway hopper car having a hopper discharge opening, formed in part by converging metallic hopper sheets, the combination of an outlet frame formed with a top portion having an opening therein registering with said hopper discharge opening, means securing said top portion to the metallic hopper sheets, frame side and end walls depending from said top portion in laterally outwardly spaced relationship to the edges of said hopper discharge opening, doors hinged on said end walls by hinge rods spaced laterally outward from the edges of the opening and extending through the end walls adjacent said top portion at each side of said opening, said doors swinging when open into the space between the side walls of the frame and the adjacent edges of the hopper discharge opening, door operating rods pivotally carried by said end walls adjacent the lower edges thereof and adjacent the side walls, said operating rods having a portion thereof extending through at least one of said end walls, and operating means secured to said rod extensions exterior of the frame, said hinge rods and operating rods being sealed with respect to the frame thereby preventing entrance of foreign matter into the frame through the side walls thereof.

5. In a railway hopper car having a hopper discharge opening formed in part by converging metallic hopper sheets, the combination of an outlet frame formed with a top portion having an opening therein registering with said hopper discharge opening, means securing said top portion to the metallic hopper sheets, frame side and end walls depending from said top portion and terminating in outwardly directed flanges, said side and end walls being spaced laterally outward from the edges of said opening, a safety sealing plate removably carried by said flanges, doors hinged on certain of said walls by hinge rods spaced laterally outward from the edges of said opening and located adjacent said top portion and swingable when open into the space between

the adjacent frame wall and discharge opening, door operating rods pivotally carried by certain of said walls adjacent the lower edges thereof and at either side of the discharge opening, said operating rods having extensions thereof projecting through the frame, and operating means secured to said rod extensions exterior of the frame, said hinge rods and operating rods being sealed with respect to the frame thereby cooperating with said safety sealing plate in preventing entrance of foreign matter into the frame.

6. In a railway hopper car having a hopper discharge opening formed in part by converging metallic hopper sheets, the combination of an outlet frame formed with a top portion having an opening therein registering with said hopper discharge opening, means securing said top portion to the metallic hopper sheets, frame side and end walls depending from said top portion in laterally outwardly spaced relationship to the edges of said hopper discharge opening, doors hinged on said end walls by hinge rods extending through the end walls and located adjacent said top portion at each side of said opening, door operating rods pivotally carried by said end walls adjacent the lower edges thereof and adjacent the side walls, said operating rods having a portion thereof offset and adapted to cam said doors to a closed position, operating means secured to said door operating rods exteriorly of the frame, and locking means engageable with said operating means to secure the doors in closed position.

7. In a railway hopper car having a substantially horizontal hopper discharge opening formed in part by converging metallic hopper sheets, the combination of an outlet frame comprising a substantially horizontal top portion formed with an opening therein registering with said hopper discharge opening, said top portion extending laterally of said opening, substantially vertically extending frame side and end walls spaced outwardly of vertical planes through the edges of said opening and being connected to said top portion, doors hinged to certain of said walls adjacent the top portion of the frame and having their free edges meeting adjacent a center line of the frame to close the discharge opening, said hinges being spaced laterally outward from the edges of the opening, said doors when open being retained in substantially vertical position by said frame side walls and being located outwardly of the vertical planes through the sides of the discharge opening.

8. In a railway hopper car having a substantially horizontal hopper discharge opening formed in part by converging metallic hopper sheets, the combination of an outlet frame comprising a substantially horizontal top portion formed with an opening therein registering with said hopper discharge opening, said top portion extending laterally of said opening, substantially vertically extending frame side and end walls spaced outwardly of vertical planes through the edges of said opening and being connected to said top portion, doors hinged to certain of said walls adjacent the top portion of the frame and having their free edges meeting adjacent a center line of the frame to close the discharge opening, said hinges being spaced laterally outward from the edges of the opening, said doors when open being retained in substantially vertical position by said frame side walls and being located outwardly of the vertical planes through the sides of the discharge opening, and said frame side and end walls extending downwardly beyond the free

edges of said open doors whereby said doors are wholly inclosed at all times within the frame.

9. In a railway hopper car having a substantially horizontal hopper discharge opening formed in part by converging metallic hopper sheets, the combination of an outlet frame comprising a substantially horizontal top portion formed with an opening therein registering with said hopper discharge opening, said top portion extending laterally of said opening, substantially vertically extending frame side and end walls spaced outwardly of vertical planes through the edges of said opening and being connected to said top portion, doors hinged to certain of said walls adjacent the top portion of the frame and having their free edges meeting adjacent a center line of the frame to close the discharge opening, said hinges being spaced laterally outward from the edges of the opening, said doors when open being retained in substantially vertical position by said frame side walls and being located outwardly of the vertical planes through the sides of the discharge opening, and said frame side and end walls extending downwardly beyond the free edges of said open doors whereby said doors are 25

wholly inclosed at all times within the frame, and sealing means carried by said frame side and end walls adjacent the lower edges thereof thereby wholly closing the frame against entrance of foreign matter from below.

10. In a railway hopper car having a substantially horizontal hopper discharge opening formed in part by converging metallic hopper sheets, the combination of an outlet frame secured to said hopper sheets and comprising, side and end walls spaced laterally outward of vertical planes through the edges of said discharge opening, a top portion connected to said side and end walls and extending inward for attachment to the hopper sheets, and a pair of doors hinged to said frame between the walls thereof and beneath said top portion, said hinges being spaced laterally outward from the edges of the opening, said doors when closed having their free edges 20 directed toward each other and when open being located bodily outward of the vertical planes through the adjacent edges of the hopper discharge opening.

JOHN J. McBRIDE.
VICTOR WILLOUGHBY.
